(57) **CLAIM**

The ornamental design for an LED light, as shown and described.

DESCRIPTION

FIG. 1 is a front perspective view of an LED light of the present invention;

FIG. 2 is a left side view of the LED light of FIG. 1;

FIG. 3 is a right side view of the LED light of FIG. 1;

FIG. 4 is a top side view of the LED light of FIG. 1;

FIG. 5 is a bottom side view of the LED light of FIG. 1;

FIG. 6 is a front side view of the LED light of FIG. 1; and,

FIG. 7 is a back side view of the LED light of FIG. 1.

The broken lines shown are included for the purpose of illustrating unclaimed portions of the design and form no part of the claimed design.
